UNITED STATES PATENT OFFICE

IMA P. JOHNSON AND GERTRUDE S. McMULLEN, OF HOLLYWOOD, CALIFORNIA

DESIGN FOR A CLASP

Application filed April 6, 1929. Serial No. 30,778. Term of patent 3½ years.

To all whom it may concern:

Be it known that we, IMA P. JOHNSON and GERTRUDE S. McMULLEN, citizens of the United States of America, residing at Hollywood, in the county of Los Angeles and State of California, have invented a new, original, and ornamental Design for Clasps, of which the following is a specification, reference being had to the accompanying drawing, forming a part thereof.

We claim:—

The ornamental design for a clasp substantially as shown.

IMA P. JOHNSON.
GERTRUDE S. McMULLEN.
